UNITED STATES PATENT OFFICE.

VERN L. JONES, OF DETROIT, MICHIGAN, ASSIGNOR TO THE FARRAND COMPANY, OF DETROIT, MICHIGAN, A CORPORATION OF MICHIGAN.

PNEUMATIC ADJUSTING MECHANISM FOR MUSICAL INSTRUMENTS.

1,190,767.

Specification of Letters Patent. Patented July 11, 1916.

Application filed April 10, 1913. Serial No. 760,254.

To all whom it may concern:

Be it known that I, VERN L. JONES, a citizen of the United States of America, residing at Detroit, in the county of Wayne 5 and State of Michigan, have invented certain new and useful Improvements in Pneumatic Adjusting Mechanism for Musical Instruments, of which the following is a specification, reference being had therein 10 to the accompanying drawings.

The invention relates to pneumatic adjusting mechanism, and more particularly to such a mechanism adapted for adjusting the hammer rest rail.

15 The invention has among the objects thereof to provide a pneumatic mechanism which will effect a differential adjustment; to permit the adjustments to be readily controlled; to provide means whereby each adjustment may be easily and accurately effected; and to produce a structure which will differentially adjust the hammer rest rail.

20 Other objects of the invention will more 25 fully hereinafter appear.

The invention resides in the peculiar construction, arrangement and combination of parts as will be herein described and claimed.

30 In the drawings,—Figure 1 is fragmentary side elevation of the device embodying my invention; Fig. 2 is a section through the pneumatic and the valve chamber therefor; Figs. 3 and 4 are sections at right 35 angles to each other through the control member and the valve block; Fig. 5 is a top plan view of the structure shown in Figs. 1 and 2, with certain parts removed; Fig. 6 is a bottom plan view of the control member and valve block, and Fig. 7 is an end 40 view of the structure shown in Fig. 1 combined with the control member therefor, the latter being in section.

A designates the hammer rest rail, mounted 45 in any suitable manner for movement toward and from the hammers.

C is a rod connected at its upper end to rod A upon which the rail A is pivotally mounted, rod C further having its lower 50 end operatively attached to a pneumatic D. This pneumatic is constructed to differentially adjust the rod C and to this end is provided with three collapsible sections E E' E'' connected by independent conduits 55 F F' F'' respectively to valve chambers G

G' G''. The valve chambers are each adapted to communicate by means of a port H with a vacuum chamber I operatively connected to the exhaust mechanism. Normally, communication between the vacuum and the valve chambers however, is closed by a valve J attached to a diaphragm pneumatic K and the chambers l of these diaphragm pneumatics are connected respectively by independent conduits or tubes L L' L'' with ports M M' M'', preferably formed in a valve block N and controlled by independent valves. These valves are herein illustrated as comprising flat springs P P' P'', each fixedly secured at one end as by screws Q and having the opposite end positioned in the path of an operating member R. Each of the ports M M' M'' is provided with a seat formed by a disk S of suitable material, upon which the springs 70 seat.

As shown in Fig. 3, the operating member R is in the form of a plug arranged for reciprocation in a guide bore I, and the ends of the springs are arranged to be successively engaged and released upon travel of the plug. Thus, the spring P has an up-standing lug U, the member P' a lug U' which is shorter than the lug U, while the end of the spring P'' which is in the path 85 of the plug R is flat and arranged below the plane of the upper edge of the lug U'. Therefore, upon depression of the member R the lug U will first be engaged and the port M opened. Further depression will 90 cause the plug to contact with the lug U', opening the port M', and the complete depression of the member R will open the port M''. It is to be noted that when the port M' is opened the port M is also uncovered, and similarly the ports M' and M'' are both opened when the actuating member 95 is in position to engage the spring P''. Upon the raising or outward movement of the plug the ports M'' M' M are successively 100 closed.

In order to insure the actuating member being moved to properly open the ports in the valve block N, a spring V is provided which has a projection W thereon adapted 105 to engage with notches Y Y' in the side of the plug R.

The valve chambers are each adapted to communicate with the atmosphere by means of an aperture Z but this aperture is nor- 110

mally closed by a valve X connected to be actuated by the diaphragm pneumatic K and arranged to close the aperture Z upon the opening of the port H and to open the aperture upon the closing of the port.

Normally the pneumatic is in the position shown in Fig. 1 and plug R in the raised position shown in Fig. 3 so that the ports M M' M² are closed. The rest rail A is then 10 away from the hammers. If it is desired to adjust the rest rail so as to slightly limit the stroke of the hammers, the operator depresses the plug R until the projection W engages the recess Y. This moves the 15 spring P to open the port M, establishing atmospheric pressure in the chamber of the diaphragm pneumatic K, which will cause the motor to raise the valve J from its seat, opening the port H and closing the aperture 20 Z. This will establish communication between the vacuum chamber I and the interior of the section E through the port F, causing the section E to collapse. The collapsing of the section raises the rod C and 25 thereby effects an adjustment of the hammer rest rail.

As the connections between the several ports M' M² and the sections E' E² operate in the same manner as described in connection 30 with the port M and section E, it will be readily understood that upon a further depression of the plug so that the projection W engages the recess Y' the port M' will be closed, collapsing the section E', but as 35 before stated, since the port M remains open when the port M' is uncovered, both the sections E and E' will be collapsed. This will effect a further adjustment of the hammer rest rail. Likewise upon the complete depression of the plug all three sections 40 E, E' E² will be collapsed, effecting the maximum adjustment of the rail A. When the plug is raised the port M² will first be closed, which will cause the closing of the 45 port H in the valve chamber G² and the opening of the port Z then establishes communication between this latter chamber and the atmosphere. This will place the interior of the section E² in communication with 50 the atmosphere and cause the expanding of the latter. Therefore, as the plug R is raised there will be a successive expansion of the chambers E E² E' and E, which will restore the hammer rest rail to its normal 55 position. It will be noted, however, that if the plug is depressed so as to adjust the rail to an intermediate position, the plug may be further actuated without returning the same to its normal position to cause a different 60 adjustment of the rail. Similarly when

the rail has been moved to its maximum position of adjustment, it may be placed in an intermediate position of adjustment without first returning the member R to its initial station.

65

What I claim as my invention is:

1. In a pneumatically-operated musical instrument, the combination with the hammer rest rail, of pneumatic means for differentially adjusting said rail including a 70 plurality of independently collapsible sections, valves controlling the collapsing of said sections, independent ducts leading to said valves, and manually operable means for controlling said ducts comprising a 75 valve block, provided with ports, valves controlling said ports, and a reciprocal plug moving in said block and directly contacting with and controlling said valves.

2. In a pneumatically-operated musical 80 instrument, the combination with the hammer rest rail, of pneumatic means for adjusting said rail including a plurality of independently collapsible sections, valves controlling the collapsing of said sections, 85 independent ducts leading to said valves, valves for controlling said ducts, said valves being provided with up-standing lugs in substantial alinement with each other, and means for progressively engaging said lugs. 90

3. In a pneumatically-operated musical instrument, the combination with the hammer rest rail, of pneumatic means for adjusting said rail including a plurality of independently collapsible sections, valves 95 controlling the collapsing of said sections, independent ducts leading to said valves, means for controlling said ducts, and means for slightly holding each adjustment of control.

4. In a pneumatically-operated musical instrument, the combination with the hammer rest rail, of pneumatic means for differentially adjusting said rail including a 105 plurality of independently collapsible sections, valves controlling the collapsing of said sections, independent ducts leading to said valves and manually operable means for controlling said ducts comprising a valve block, ports in said block, valves controlling 110 said ports, a reciprocal plug moving in said block and controlling said valves, said plug having spaced notches, and means for progressively engaging said notches.

In testimony whereof I affix my signature 115 in presence of two witnesses.

VERN L. JONES.
